[57] CLAIM

The ornamental design for a disc-shaped container which can hold absorbent material, as shown and described.

DESCRIPTION

FIG. 1 is a top, perspective view of a disc-shaped container which can hold absorbent material showing our new design; and,

FIG. 2 is a bottom view thereof.

The broken line showing of environmental structure in FIGS. 1 and 2 is for illustrative purposes only and forms no part of the claimed design.
